UNITED STATES PATENT OFFICE.

WALTER T. KRAUSCH, OF LA GRANGE, AND ERNST F. WEBER, OF CHICAGO, ILLINOIS.

RAIL DRILL.

Application filed March 29, 1920. Serial No. 369,453.

To all whom it may concern:

Be it known that we, WALTER T. KRAUSCH and ERNST F. WEBER, citizens of the United States, and residents of La Grange and Chicago, respectively, in the county of Cook and State of Illinois, have invented certain new and useful Improvements in Rail Drills, of which the following is a description, reference being had to the accompanying drawings, which form a part of our specification.

Our invention relates to a portable power-operated drill for drilling rails after the latter have been laid or put into place; the drill being intended to be secured to and 15 adjustably supported on a track car or truck provided with suitable motive power and arranged to move on the rails to be operated on; our improved drill being especially intended for drilling holes in the base of the 20 rail for the insertion of anchor spikes or screw-spikes as the case may be.

One object of our invention is to provide a device more especially adapted for vertical drilling operations, but which may at the 25 same time be adjusted at various inclinations or angles to a vertical plane so as to permit the device or drill to swing to opposite sides of a rail in order that drilling of the base on both sides of the rail may be 30 readily accomplished; the operation of the drill-spindle being induced through suitable mechanism operated by the motive power of the track-car or truck, while the feeding of the drill-bit is preferably ac- 35 complished manually; the hand or manually operated feed-mechanism being of such nature that the drill will be held in its ad-justed position, thus obviating the necessity for special mechanism whereby the drill- 40 spindle will be held in elevated position when the drill device is out of operation, while at the same time obviating the neces- 45 sity for the exertion of great pressure by the operator during drilling operations.

The objects and advantages of our in- 50 vention will be readily comprehended from the detailed description of the drawings, wherein:

Figure 1 is a plan view of our improved 55 rail drill shown applied to a portion of track car or truck.

Figure 2 is a side elevation of our im- 60 proved rail drill.

Figure 3 is a detail sectional view taken 65 on the line 3—3 of Figure 2 looking in the direction of the arrows.

Figure 4 is a detail sectional view, taken on the line 4—4 of Figure 2 looking in the direction of the arrows.

Figure 5 is a detail sectional view taken 60 on the line 5—5 of Figure 1 looking in the direction of the arrows.

Our invention contemplates a rail drill adapted to be secured to the platform or sills of a small track car which travels along the 65 rails to be operated on; one of the rails being shown at A in Figures 1 and 2; while the track car is preferably provided with a pair of parallelly disposed side sills 10 arranged adjacent one side of the truck or track car. 70 The device comprises a bracket or frame 11 which is provided with an integral hub portion 12 adapted to receive the spindle or shaft to which bevel gear 13 is secured; while gear 13 meshes with a power-driven 75 bevel pinion 14 which is adapted to be driven by sprocket-wheel 15 when the slidably mounted clutch 16 is in operative relation with the extended hub 17 of the sprocket 15. The sprocket 15 is adapted to be driven, in 80 the particular exemplification disclosed, by means of a suitable sprocket chain 18 which is disposed about a drive sprocket secured on the power shaft 19 of an internal combustion or other suitable motor indicated 85 at 20.

The bracket or frame member 11 is pro- 90 vided with a number of parallelly disposed and spaced arms 21, 22 and 23, each of which terminates in a hub portion apertured to receive a shaft 24. The shaft 24 at a 95 point intermediate of arms 22 and 23 is pro- vided with a bevel pinion 25 keyed thereto and arranged in mesh with the bevel gear 13, so that shaft 24 will be rotated when power is transmitted to bevel pinion 14 through movement of clutch 16 into clutching relation with the clutching surface on hub 17 of sprocket 15. The shaft 24 at a point intermediate of arms 21 and 22 of bracket 11 is 100 provided with a gear 26 secured to the shaft so as to rotate therewith. The gear 26 is arranged in mesh with a gear 27 secured to a sleeve 28 through which the drill-spindle 29 extends. The sleeve 28 is rotatably 105 mounted at its ends in suitable bearings 30, 30 provided on a frame member or yoke 31, which, like the frame member 11, is prefer- ably of the skeleton or open formation for the sake of lightness in weight. The ends 110 of the frame member 31 terminate in suitable apertured hub portions for the passage

of the shaft 24 therethrough; in other words, shaft 24 also acts as a journal for the frame member 31 so as to permit sidewise oscillation of the frame member 31. The upper end or arm of frame member 31 is intended to overlap the end of arm 21 of frame member 11 while the lower end or arm of frame member 31 overlaps the lower side of arm 23 of frame member 11 and the ends of shaft 24 are provided with suitable collars 32, 32 whereby the shaft is held against longitudinal movement and the frame members and various elements carried thereby maintained in operative relation with one another.

15 It is clearly evident from the construction shown and described that frame member 31, with the elements carried thereby, may be swung laterally so as to be disposed to either side of the vertical plane of frame member 11; that is frame member 31 with the mechanism carried therein may be swung to either side of the rail A which is being operated on.

20 The sleeve 28 is rotatably mounted in the arms of frame member 31; the sleeve extending into the bearing portions 30 of the frame member 31 as shown in Figure 3 and provided with suitable bushings as at 32^a. The sleeve 28 at its upper end is provided 25 with a suitable collar 33 secured thereto and in abutting relation with the bearing portions 30 of the frame member 31, to prevent upward longitudinal movement of the sleeve; while the lower end of the sleeve at a slight 30 distance above the lower bearing portion 30 of frame member 31 is provided with a collar 34 secured thereto against movement lengthwise of the shaft but adapted to rotate therewith. At a point intermediate of collar 34 and the bearing portion 30, sleeve 28 is provided with anti-friction thrust bearings 35 which enable free rotation of the sleeve. The drill-spindle 29 is disposed through sleeve 28 and provided with slots 30 or key-ways 36 extending lengthwise of the drill-spindle, to receive suitable feathers 37 whereby the drill-spindle and sleeve are rotatably secured together, while at the same time permitting the drill-spindle to move 45 lengthwise of the sleeve. The drill-spindle 29 terminates at its lower end in a suitable drill-chuck, as at 38, to receive the drill-bit shown at 39, which may be held in the chuck in any suitable manner, as for example by a 50 set-screw 40.

55 The drill-spindle 29 at its upper end is provided with suitable means for feeding the drill-spindle into drilling position.

60 In the particular exemplification, the upper end of drill-spindle 29 is provided with an elongated cylindrical head 41 having pins or lugs 42 which extend into an annular groove formed in the spindle 29, see Figure 3, thus permitting the spindle 29 to have 65 rotation independently of head 41. The

head 41 is externally threaded throughout a considerable portion of its length. The frame portion 31 is provided with a yoke 43 extending above the frame portion and the yoke is provided with an internally threaded hub adapted to receive the externally threaded head 41, which latter at its upper end above the yoke 43 is provided with a suitable hand-wheel 44. With the construction just described, the operator may force the drill-spindle 29 downwardly into operative or drilling position by turning hand-wheel 44 in proper direction so as to screw the head 41 through the threaded hub in yoke 43, thereby causing the drill-spindle so also to be forced downwardly. It is also evident that the drill-spindle will be maintained in raised or any desired position by turning the hand-wheel and head in the proper direction.

65 The composite frame 11—31, with the mechanisms carried thereby, is supported through the medium of the hub portion 12 of frame 11; the hub portion being adapted to receive an elongated sleeve 45 which, in turn, receives the spindle or shaft 46 to which bevel gear 13 is secured; the sleeve being of length to also extend through openings arranged in alignment at opposite ends of supporting frame member 47, see Figure 1. The frame member 47 is shown rectangular in formation to fit between the side sills 10. The frame member 47 may be more or less skeleton form with the sides flanged so as to overlap the side sills 10 to 100 which the flanges are bolted or otherwise secured. The two end portions of the frame member 47 are provided with openings therethrough, to receive the sleeve 45; the openings and the sleeve 45 being provided 105 with key-ways for the reception of suitable keys as shown at 48 which will prevent rotation of sleeve 45 in supporting frame member 47. The hub portion 12 of frame 11 is also provided with a key-way or slot which is adapted to receive a bearing-strip which has frictional relation with the sleeve 45; the bearing-strip is intended to receive the downward pressure exerted by the end of set-screw or bolt 49 which passes through a 110 tapped opening in a boss 50 formed on hub 12. It is apparent that when set-screw 49 is screwed downwardly a firm frictional relation between frame 11 and the sleeve 45 will be provided, sufficient to hold frame 11 in any adjusted or oscillated position, due 115 to the fact that the sleeve 45 cannot rotate in the supporting casting or frame 47 because of the keys 48. The spindle 46 of gear 13 extends entirely through the sleeve 120 and is provided at the outer end with a collar 51 so as to prevent longitudinal movement of the spindle; the hub of gear 13 having abutting relation with the inner end of sleeve 45 and the hub of frame 11. 125

It is evident from the construction shown and described that the composite frame 11-31 may be oscillated through the arc of a vertically disposed circle, about the sleeve 45 upon releasing set-screw or bolt 49; the various gears 13, 14 and 25 being so related as to permit the oscillation of the frame without interfering with the operative relation between the gears. With the frame of the device fulcrumed as just described, it is apparent that the drill-spindle may be swung into a plane where the spindle will clear the ball of the rail A, permit drilling of the rail-base and provide a hole substantially at right angles to the sloping upper surface of the rail base.

The pivoted connection between frame members 11 and 31 formed by the shaft 24 enables the frame-section 31 to be swung through the arc of a horizontally disposed circle so as to position the drill-spindle on opposite sides of the rail; the gears 26 and 27 being kept in constant meshing relation with one another.

The power for operating the drill may be obtained from a suitable motor on the track car or truck, which may also be driven by the motor; power to the drive gear 14 being controlled by a suitable clutch 16 as previously described; and instead of employing the sprocket and sprocket-chain method of imparting power to the gear 14, any other suitable means may be employed.

We have shown and described what we believe to be a simple embodiment of the invention, but alterations may be made in certain details of construction, without, however, departing from the spirit of our invention.

What we claim is:—

1. A rail drill of the character described, comprising, in combination with a track-car provided with motive power and a drive-shaft, a composite frame adjustably carried by the car, the composite frame consisting of a vertically disposed skeleton frame-section secured to the car so as to permit adjustment about a horizontally disposed axis, a train of gears carried by said section and adapted to have operative relation with said drive-shaft, a second vertically disposed skeleton frame-section oscillatably secured to the first section so as to swing laterally about a vertically disposed axis, a sleeve rotatably mounted in said second frame-section, means intermediate of said sleeve and the train of gears whereby the sleeve may be rotated, a drill-spindle slideable in said sleeve and adapted to be rotated thereby, and means intermediate of the drill-spindle and said second frame-section whereby the operative position of the drill-spindle is controlled.

2. A rail drill of the character described, comprising, in combination with a track-car,

a composite frame consisting of a vertically disposed frame-section adjustably mounted on the track-car so as to swing about a horizontally disposed axis, a second vertically disposed frame-section oscillatably secured to the first section to swing laterally about a vertically disposed axis, a sleeve rotatably mounted in said second frame-section against longitudinal movement, a train of gears carried by the frame-sections and operatively connected with said sleeve, a drill-spindle slideably mounted in said sleeve and adapted to rotate therewith, means whereby power may be imparted to the train of gears, and means whereby the first frame-section may be held in its adjusted positions.

3. In combination with a track-car provided with motive power, a rail drill comprising a composite frame consisting of a frame-section adjustably secured to the car to swing through the arc of a vertically disposed circle, means whereby the frame-section may be held in its adjusted position, a second frame-section oscillatably secured to the first section to swing through the arc of a horizontally disposed circle, a sleeve member rotatably mounted in said second frame-section, a drill-spindle slideably feathered in said sleeve member, means loosely secured to the end of the drill-spindle to permit independent rotation of the spindle and said means, said means having screw thread connection with a portion of said second frame-section and adapted to cause longitudinal movement of the drill-spindle and thereby control the operative position of the latter, and means intermediate of the motive power and said sleeve member whereby the latter with the drill-spindle may be rotated.

4. In a drill of the character described, a pair of frame-sections pivotally secured together, one of the sections being mounted to swing through the arc of a vertically disposed circle while the other section is adapted to move through the arc of a horizontally disposed circle, a sleeve-member disposed vertically and rotatably mounted in said second section, a drill-spindle feathered in said sleeve-member, a yoke portion secured to said second mentioned section, a head swiveled on the upper end of said drill-spindle to rotate thereon, said head being externally threaded and passing through a threaded aperture in said yoke portion whereby the vertical position of the drill-spindle may be controlled, and a train of gears carried by the frame-sections whereby said sleeve and the drill-spindle may be rotated.

5. A drill of the class described, comprising, in combination with a track-car provided with motive power, a supporting member secured to the car, a frame-section jour-

nalled in said supporting member so as to swing through the arc of a vertically disposed circle, a second frame-section journaled on the first section so as to swing 5 through the arc of a horizontally disposed circle, a drill-spindle rotatably and slidably mounted in the second frame-section, a train of gears mounted in both frame-sections, intermediate of the motive power and the 10 drill-spindle whereby the latter is rotated, manually operated means carried by the second frame-section whereby the position of the drill-spindle is controlled, and means whereby the adjusted position of the first 15 frame-section relative to the supporting member may be maintained.

6. In combination with a track-car provided with motive power, a rail drill comprising an apertured supporting member 20 adapted to be secured between the side sills of the car, a sleeve mounted in the aperture of said member against rotation and dis-

posed horizontally, a gear carrying spindle rotatably mounted in said sleeve, a frame section oscillatably mounted on said sleeve 25 to swing through the arc of a vertically disposed circle, means whereby the frame section may be locked in place on said sleeve, a second frame section oscillatably mounted on the first frame section to swing through 30 the arc of a horizontally disposed circle, a drill-spindle rotatably mounted in said second frame section, means whereby the drill-spindle may be moved longitudinally and maintained in adjusted positions, and means 35 intermediate of the gear carrying spindle and the drill-spindle whereby the latter may be rotated.
